TOOL HOLDER

Filed March 29, 1928

INVENTOR.
Joseph Janda
BY *Leprince*

ATTORNEY.

UNITED STATES PATENT OFFICE.

JOSEPH JANDA, OF RIDGEWOOD, NEW YORK.

TOOL HOLDER.

Application filed March 29, 1928. Serial No. 265,617.

My invention relates to tools and more particularly cutting tools, such as saws and the like, and the particular object of the present invention is to produce a holder for such 5 tools whereby the person using the tool is enabled to quickly adjust the tool to any desired position to be used in any plane.

For a complete understanding of my invention, I refer to the appended drawing in 10 which I have shown, by way of illustration, an embodiment of the invention as applied to hack-saws and in which Fig. 1 is a side elevation of a hack-saw, a portion of the holder and blade being broken away, Fig. 2 a 15 front elevation showing the saw-blade adjusted to a different plane, Fig. 3 a fragmentary view showing the means for placing the blade at a different angle relative to the holder, and Fig. 4 a section along line 4—4 20 in Fig. 3.

In the drawing, 1 is the U-shaped holder having the parallel arms 2 and 3. The handle which is shown at 4 is provided near its inner end with two round holes extending at 25 right angles to each other, the hole nearer the inner end being shown at 5 in Fig. 1. These holes are adapted to receive the end of the arm 2 of the holder 1. By means of a screw having a milled head 6, the end of 30 arm 2 is securely held in either of said holes against rotation. The saw-blade shown at 7 is fastened with its end in small chucks 8 and 9, respectively. Each chuck is formed with a lug 10 and a fork 11 having a hole for a 35 pivot pin 12 to pass through whereby the chucks are pivotally connected respectively with the inner end of the handle 4 and the inner end of a screw-bolt shown at 13. This 40 screw-bolt passes through the enlarged end of a bearing member 14 being swivelled on the arm 3 of holder 1. By means of a wing-nut 15 engaging the bolt 13, the latter can be displaced in either direction to either tighten or relax the saw-blade. A small screw 45 shown at 16 which enters a longitudinal groove 17 cut in the bolt prevents the latter from turning in member 14. A second groove in the bolt is shown at 18, which is used to register with screw 16, in case it is 50 desired to place the saw-blade at right angles

to the arms of the holder, in which case the bolt is turned about 90°, whereas arm 2 of the holder 1 is passed through hole 5 near the inner end of handle 4.

At 19 in Figs. 1 and 3 is shown a small 55 screw, which when tightened holds the bearing member 14 against rotation on arm 3.

Fig. 2 shows, how the saw-blade may be offset relative to the arms 2 and 3 of the holder so as to occupy a different plane. 60

In order to place the saw-blade in this position, one first screws the wing-nut 15 in a direction to relax the saw-blade. Then the screws 6 and 19 are loosened and the handle 4 and the member 14 are turned respectively 65 about the arms 2 and 3 of the holder into the positions shown in Fig. 2. Thereupon the screws 6 and 19 are tightened and if necessary the wing-nut 15 is also given a few turns to make the saw-blade sufficiently taut. 70

It will be readily seen that by the means above described the saw-blade can be given any desired position relative to the holder. For instance, instead of the handle 4 and the member 14 being turned in the same direction, they can also be turned in opposite directions. Also, as already indicated above, the saw-blade can be placed in a position at right angles to the position shown in Fig. 1, and when in said position can be offset relative to the arms of the holder. 75

While I have shown and described my invention as applied to a hack-saw, it is obvious that it can also be applied to similar tools in which the operating element is supported at its ends, and furthermore, I do not, of course, limit myself to the details of the embodiment as shown because changes may be made therein without a departure from the essence of my invention. 80

I claim:

1. In a tool-holder, the combination with a holding frame, of means adapted to be angularly displaced relative to the ends of said holding frame about the axes of said ends, 95 means adapted to support a tool at its ends and being pivotally connected parallel to the axes of said ends with said first-mentioned means so as to position the tool at any desired angle relative thereto, and means causing a 100

longitudinal relative displacement between said first-mentioned means.

2. The combination as specified in claim 1, including means for securing said first-mentioned means in any position on said holding frame.

3. In a tool-holder, the combination with a holding frame, of swivel members adapted to be angularly displaced relative to the ends 10 of said holding frame about the axes of said ends, means adapted to support a tool at its end and being pivotally connected parallel to the axes of said ends with said first-mentioned means so as to position the tool 15 at any desired angle relative thereto, means for securing said swivel members in any position on said holding frame, and means causing a longitudinal relative displacement of said swivel members.

20 4. In a holder for saw-blades, the combination with a holding frame having substantially parallel arms, of a handle mounted to be rotative about the longitudinal axis of one of said arms, a bearing member mounted to 25 be rotative about the longitudinal axis of the other arm, a longitudinally adjustable element received in said bearing member, pivotal members connecting the ends of the saw-blade and the said element and the inner end 30 of said handle, said pivotal members pivoting about axes parallel to the longitudinal axes of said arms, and means for producing a displacement of said longitudinally movable member.

35 5. The combination as specified in claim 4, including means for securing said handle and said bearing member at various angular positions relative to the respective arms of said holding frame.

40 6. The combination as specified in claim 4, including means for holding said element against rotation in said bearing member.

In testimony whereof I affix my signature.

45

JOSEPH JANDA.
